CLAIM

The ornamental design for a wireless label maker, as shown and described.

DESCRIPTION

FIG. 1 is a perspective view of a wireless label maker showing our new design;

FIG. 2 is a bottom perspective view of the wireless label maker of FIG. 1;

FIG. 3 is a top view of the wireless label maker of FIG. 1; FIG. 4 is a bottom view of the wireless label maker of FIG. 1;

FIG. 5 is a front view of the wireless label maker of FIG. 1; FIG. 6 is a rear view of the wireless label maker of FIG. 1; FIG. 7 is a right side view of the wireless label maker of FIG. 1; and,

FIG. 8 is a left side view of the wireless label maker of FIG. 1

The broken lines in the figures illustrate the portions of the design that form no part of the claimed design.

1 Claim, 6 Drawing Sheets
